(57) **CLAIM**

The ornamental design for a photocast electrophoresis gel caster as shown and described.

DESCRIPTION

FIG. 1 is a three-quarter view of a photocast electrophoresis gel caster shown in a closed configuration;

FIG. 2 is a front side view thereof;

FIG. 3 is a rear side view thereof;

FIG. 4 is a right-side view thereof;

FIG. 5 is a left side view thereof;

FIG. 6 is a top side view thereof;

FIG. 7 is a bottom side view thereof;

FIG. 8 is a three-quarter view of the photocast electrophoresis gel caster shown in an open configuration;

FIG. 9 is a front side view thereof;

FIG. 10 is a rear side view thereof;

FIG. 11 is a right-side view thereof;

FIG. 12 is a left-side view thereof;

FIG. 13 is a top side view thereof; and,

FIG. 14 is a bottom side view thereof.

The broken lines in the drawings depict portions of the photocast electrophoresis gel caster that form no part of the claimed design.
